UNITED STATES PATENT OFFICE.

ALLAN GORDON SMITH, OF LONDON, ENGLAND.

DESIGN FOR AN ELECTRIC LIGHTER FOR SMOKERS' USE.

Application filed November 12, 1927. Serial No. 24,092. Term of patent 14 years.

To all whom it may concern:

Be it known that I, ALLAN GORDON SMITH, subject of the King of Great Britain, residing at London, England, have invented a new, original, and ornamental Design for an Electric Lighter for Smokers' Use, of which the following is a specification, reference being had to the accompanying drawings, forming a part thereof.

Figure 1 is a perspective view of an elec-

tric lighter for smokers' use embodying my design; and

Figure 2 is a side elevation of the same.

Figure 3 is a front elevation.

I claim:

The ornamental design for an electric lighter for smokers' use as shown.

In testimony whereof I have hereunto set my hand.

ALLAN GORDON SMITH.
